UNITED STATES PATENT OFFICE.

JONAS B. ERICKSON, OF IRON MOUNTAIN, MICHIGAN.

SPIKE-PULLER.

1,380,196.

Specification of Letters Patent. Patented May 31, 1921.

Application filed May 11, 1920. Serial No. 380,532.

To all whom it may concern:

Be it known that I, JONAS B. ERICKSON, a citizen of the United States, and a resident of Iron Mountain, in the county of 5 Dickinson and State of Michigan, have invented a new and Improved Spike-Puller, of which the following is a full, clear, and exact description.

This invention relates to improvements in 10 spike pullers, an object of the invention being to provide a device which facilitates the removal of spikes and which employs a lever positioned parallel with the rail and operating in this position to remove spikes from 15 either side of the rail.

A further object is to provide a spike puller which is especially adapted for use on 20 bridges, trestles, and elevator work where it is difficult to employ the ordinary type of spike puller.

A further object is to provide a spike puller which can be quickly and effectually placed in operative position and which will 25 efficiently remove the spike with the minimum of effort on the part of the operator.

With these and other objects in view the invention consists in certain novel features of construction, and combinations and arrangements of parts, as will be more fully 30 hereinafter described and pointed out in the claims.

In the accompanying drawings—

Figure 1 is a perspective view illustrating my invention in operative position.

Fig. 2 is a fragmentary view in section on the line 2—2 of Fig. 1.

1 represents a rail, 2 a tie supporting the same, and 3 a spike securing the rail to the tie. My improved spike puller comprises 40 four main parts; namely, a standard 4, a lever 5 fulcrumed on the standard 4, and a claw 6 connected by a link 7 with the lever 5.

The standard 4 comprises two members 45 8 and 9, said members adjacent their lower ends crossed and pivotally connected by a hinge pin 10. The lower extremities of these members 8 and 9 are made hook shaped forming jaws 11 adapted to grip the head 50 portion 12 of the rail 1. The upper end of the member 9 carries a bolt 14 which projects through a recess 13 in the member 8 and a lever nut 15 is provided on the bolt so that the upper ends of these members 8 and 55 9 can be drawn toward each other to oper-

ate the jaws 11 and effectually grip the rail holding the standard 4 in vertical position.

The lever 5 is provided near one end at its opposite edges with recesses 16 adapted to receive the bolt 14 in either of them so as 60 to efficiently fulcrum the lever on the bolt.

The link 7, above referred to, is made with a bifurcated upper end 17 receiving the shorter end of lever 5 and pivotally connected thereto by means of a pin or other pivotal 65 connection 18. The link 7 throughout its lower portion is made with a longitudinal slot or recess 19 and in the lower portion of this slot or recess 19, the claw 6, above referred to, is mounted and pivotally connected 70 by means of a pin or other connection 20.

The claw 6 is curved and is of substantially the shape of the letter C, the lower free end of the claw 6 having a V-shaped recess 21 at its ends to accommodate the 75 shank of the spike 3 and engage under the head of the spike as is customary in the art.

A shoulder or enlargement 22 is formed on the intermediate portion of the claw 6 and is adapted to receive a blow from a 80 hammer or other suitable device to drive the claw into operative engagement with the spike and to start the initial movement of the spike if such means is found necessary.

A coiled spring 23 connects the claw 6 with the link 7 and elastically holds these parts in proper relative position to each other, but compensates for the varying movements of the link and claw during the 90 operation of removing the spike.

It will be noted that with my improved spike puller, the lever 5 is positioned parallel to the rail 1 and the relative position of these parts is the same whether the claw 95 be operating on one side or the other of the rail. This is important in the removal of spikes on bridges, trestles, and the like where it is difficult for the operator to find standing room at the side of the rail.

The operation is as follows: The standard 4 is positioned in clamping engagement with the rail 1 and secured in such position by means of the bolt 14 and nut 15. The lever 5 is then placed in fulcruming position 105 on the bolt 14 and the claw 6 located in engagement with the spike 3. If necessary, a blow may be imparted to the claw to secure a firm engagement with the spike and initially move the same. When the parts are 110

in this position, a downward pressure on the free end of the lever 5 will operate to remove the spike as will be readily understood. By making the claw 6 of the general 5 curved or C-shape shown, the latter has a leverage against the tie and hence, the action of removing the spike is facilitated.

Various slight changes might be made in the general form and arrangement of parts 10 described without departing from the invention, and hence I do not limit myself to the precise details set forth, but consider myself at liberty to make such changes and alterations as fairly fall within the spirit 15 and scope of the appended claims.

I claim:

1. A spike puller, comprising a standard, a lever fulcrumed on the standard, a link pivotally connected to one end of the lever, 20 and a curved claw pivotally connected to the link and disposed at an angle to the plane of the lever.
2. A spike puller, comprising a standard, a lever fulcrumed on the standard, a link 25 pivotally connected to one end of the lever, a curved claw pivotally connected to the link and disposed at an angle to the plane of the lever, and a coiled spring connecting the link and the claw.
3. A spike puller, comprising a standard, 30 a lever fulcrumed on the standard, a link

pivotally connected to one end of the lever, a curved claw pivotally connected to the link and disposed at an angle to the plane of the lever, a coiled spring connecting the link and the claw, and an enlargement on 35 said claw adapted to receive blows to drive the claw into operative engagement with the spike.

4. A spike puller, comprising a standard, 40 said standard consisting of two members pivotally connected, the lower ends of said members constituting jaws adapted to grip a rail, a bolt connecting the upper ends of said members, an adjusting nut on said bolt 45 clamping the members in operative position, a lever adapted to fulcrum on the bolt, a link depending from the lever, a claw connected to the link and disposed at an angle to the plane of the lever, and a spring connecting the claw and the link. 50

5. A spike puller, comprising a standard adapted to be secured to a rail, a lever fulcrumed on the standard and adapted to be located in the same vertical plane as the rail, 55 a link on one end of the lever, and a C-shaped claw pivotally connected at one end to the link and disposed at an angle to the plane of the lever and adapted at its free end to engage spikes at either side of the 60 rail.

JONAS B. ERICKSON.
